(57) **CLAIM**

The ornamental design for a hand dryer, substantially as shown and described.

DESCRIPTION

FIG. 1 is a front, raised perspective view of a hand dryer according to a first embodiment of the invention; FIG. 2 is a front view of the hand dryer of FIG. 1; FIG. 3 is a rear view of the hand dryer of FIG. 1; FIG. 4 is a right side view of the hand dryer of FIG. 1; FIG. 5 is a left side view of the hand dryer of FIG. 1; FIG. 6 is a top view of the hand dryer of FIG. 1; FIG. 7 is a bottom view of the hand dryer of FIG. 1; FIG. 8 is a front, lowered perspective view of the hand dryer of FIG. 1;

FIG. 9 is a front, raised perspective view of a hand dryer according to a second embodiment of the invention; FIG. 10 is a front view of the hand dryer of FIG. 9; FIG. 11 is a rear view of the hand dryer of FIG. 9; FIG. 12 is a right side view of the hand dryer of FIG. 9; FIG. 13 is a left side view of the hand dryer of FIG. 9; FIG. 14 is a top view of the hand dryer of FIG. 9; FIG. 15 is a bottom view of the hand dryer of FIG. 9; and, FIG. 16 is a front, lowered perspective view of the hand dryer of FIG. 9.

The broken-lines shown on the surface of the drawings show portions of the hand dryer that form no part of the claimed design. The boundary lines in the drawings show a symbolic break in the width of the hand dryer and form no part of the claimed design. All surfaces not shown form no part of the claimed design.

1 Claim, 14 Drawing Sheets
